MACHINERY

Paul N. Dubuc, Danielson, Conn.

Application April 20, 1931, Serial No. 531,504

6 Claims. (Cl. 271—2.1)

This invention relates to improvements in mechanism for conveying, facilitating inspection, measuring and cutting sheet materials together with improved means and processes for carrying out these operations either singly or in any combination one with the other.

The principal object of the invention is to provide improved means and processes for conveying, facilitating inspection, measuring and cutting sheet materials and for carrying out the various operations either singly or in any combination one with the other.

Another object of the invention is to provide an improved machine of the above character which may be quickly and easily adapted to several specific uses.

Another object of the invention is to provide improved means for automatically grasping and holding the sheet material during the performing of the various operations thereon and for automatically releasing the said material after the various operations have been completed.

Another object of the invention is to provide improved cutting means which may be guided in irregular paths during the cutting operation so that irregularities which determine the path of the cut across the material may be followed or compensated for.

Another object of the invention is to provide improved means whereby the machine may quickly and easily be adjusted to various productive requirements.

Another object is to provide improved means for varying the operating movements of the machine.

Another object is to provide improved means whereby the conveying, measuring and cutting operations may be performed automatically either singly or in various combinations one with the other.

Another object is to provide automatic means for controlling the operation of the cutter member during the operation of the machine.

Another object is to provide automatic brake means for controlling the movement of the conveyor or measuring device during the operation of the machine.

Another object is to provide automatic means for obtaining measurements of the material during the operation of the machine.

Another object is to provide improved means for supporting the material on which the various operations are to be performed.

Another object of the invention is to provide improved means for controlling the length of cut.

Another object of the invention is to provide simple, efficient and economical means for increasing the production of articles formed from sheet materials, reducing the floor space usually necessary in the production of such articles and for decreasing the cost and many laborious and impractical productive operations of the past.

Objects and advantages of the invention will become apparent from the following description taken in connection with the accompanying drawings and it will be understood that many changes may be made in the details of construction, arrangement of parts and steps of the processes without departing from the spirit of the invention as expressed in the accompanying claims. I, therefore, do not wish to be limited to exact details of construction, arrangement of parts and processes shown and described as the preferred forms only have been shown by way of illustration.

It is to be understood that although this device has been shown and described for use in producing articles from sheet materials it may be employed for conveying, cutting, measuring or facilitating the inspection of any materials and may be employed specifically for any one of the above purposes or in various combinations one with the other.

- 10 In the production of articles formed from sheet materials it has been customary in the past to provide several long table members, measuring from 30 to 40 feet in length. The purpose of these tables was to provide means whereby a 15 relatively long strip of material could be placed thereon so that it could be readily inspected, measured and cut to desired lengths, the cutting operation being performed in most instances by a large pair of manually operated shears.
- 20 The usual practice was to grasp an end of the material and draw it the full length of the table top. The material was thence definitely arranged relative to spaced indication marks on said top and was thence inspected and cut, the 25 indication marks being used as means for determining the positions of the cuts. The material was thence removed from the table top and the various operations repeated.

It is quite apparent that this procedure required 30 an exceedingly large floor space, necessitated excessive lighting and heating apparatus and also forced the operators to do an excessive amount of walking, cutting, etc. This not only required much time but was very costly. It was also 35 found from past experience that these operations were so tiresome and laborious that the operators were soon forced to abandon their work. This resulted, in most instances, in the work being performed by unskilled labor and proved 40 to be very unsatisfactory.

Another serious defect was that a slight breeze, such as the movement of the operator walking near the table, would cause the material to be 45 displaced from the top thereof. This not only necessitated its being picked up, but in many instances caused it to become spotted and spoiled.

The present invention is, therefore, particularly directed to obviating these undesirable features by providing a relatively short table like 50 member having an endless intermittently movable top portion thereon. The said top portion is provided with means by which the material is automatically grasped for intermittent advancement past the operator.

55 During the time interval between each intermittent movement, the material is inspected and cut. Continued movement of the top portion advances the material to a position wherein it is automatically released and dropped into a receptacle. The table member is provided with means for automatically measuring the material as it is intermittently advanced thereover.

This arrangement requires but little floor 65 space, reduces the cost of manufacture, reduces the usual lighting and heating requirements of the past, increases production, and obviates the walking and many other tiresome and laborious productive operations of the past.

70 Referring more particularly to the drawings wherein like reference characters designate like parts throughout the several views, the device embodying the invention comprises a main support frame 1 having a pair of rolls 2 and 3 rotatably mounted thereon, one adjacent each end of the frame. The said rolls are connected by a

5 belt like member 4 which is formed of canvas, leather or any suitable material. The said belt 4 as shown in Fig. I is provided with a plurality of spaced tapered transverse rod members 5 which are adapted to engage in a plurality of spaced tapered slots or grooves 6 formed in the face of the rolls 2 and 3. The belt like member 4 is also provided with a plurality of definitely spaced plate members 7 which are attached directly to the belt 4 by rivets or like means 8 as 10 shown in Fig. III. A plurality of weight like holding members 9 are hinged at 10 to plate members 11 mounted on the belt like member 4 and are adapted to automatically grasp and hold the sheet material 12 on said belt like member. 15 The plate members 11, as shown in Fig. II are provided with flanged edges 13 which extend upwardly adjacent one side of the weights 9 to provide means for increasing the gripping and holding action of said weights.

20 Motion is imparted to the machine through the roll 2 which is connected with a train of gears 14, 15 and 16 which are intermittently driven by a ratchet wheel 17 mounted on the shaft 18. The ratchet wheel 17 is driven by a pawl 19 which is pivoted to a rock lever 20 mounted on the shaft 18. Motion is transmitted to the rock lever 20 through a link 21 connected with a crank 36. The said crank is driven by motion transmitted through the gears 22 and 23, pulley 24, belt 25 and pulley 26 from the motor 27 or any suitable 30 source of power.

A friction speed retarding device comprising a 35 grooved pulley 28, connected to the axle 29 of the roll 2, belt like member 30 and weight 31, provides means for instantly stopping the rotary motion of the rolls 2 and 3 and belt like member 4 after they have been advanced the desired amount.

40 A support plate 32 having depending ends 33 thereon is mounted beneath the belt like member 4 and provides means for preventing the said belt from sagging and also provides a support for a cutting device 34. The cutting device 34 is provided, as shown in Figs. I and VI, with a cutting disc 35 which is driven by a motor 37 or any suitable source of power. The cutting device 34 is mounted on a rod 38 which is slidably mounted between a plurality of roller bearings 39 in a slide block 40.

45 The slide block 40 is pivoted at 41 to a bifurcated support 42 which is itself pivoted at 43 in a bearing 44 mounted on an extension of the plate 32. The slide rod 38 is provided with a balance weight 45 adjacent its end opposite the cutting device 34. A handle member 46 adjacent the weight 45 provides means whereby the cutting disc 35 may be manually operated and guided during the cutting operation. A second handle member 47 is provided adjacent the cutting disc 35 to provide additional means by which the said cutting disc may be guided during the cutting operation. The handle 46 being provided for use when it is desired to push the cutting disc 35 across the material to be cut and the handle 47 for use when it is desired to pull the cutting disc 35 across the material to be cut. A spring member 48 is adapted to tilt the slide block 40 on its pivot 41 and simultaneously raise the cutting device 34 from the work and cause it to 55 slide downwardly toward the block 40 when the guiding handle 46 or 47 is released. This provides automatic means for returning the cutting disc to its initial set after each cutting operation 60 has been performed. A guide wheel 50 is rotat-

ably mounted on the cutting device 34 and is adapted to engage with a plate member 7 during the cutting operation. A suitable stop projection 148 is formed on some of the plate members 7 to provide means with which the cutting device 34 will abut and stop when it is desired to prevent cutting the material its full width.

Attention is directed to the fact that the plate members 7 are so spaced on the belt like member 4 and that the motion of the machine is so adjusted that each intermittent movement of the belt like member 4 causes each plate member 7 to advance a distance equal to the space between the said plate members and thereby causes each plate member to assume the position previously occupied by the advanced plate member. Each plate member 7 is adapted to be successively aligned with the cutting device 34 during the operation of the machine.

The material 12 to be conveyed, measured, inspected or cut is in this instance in the form of a long strip which is folded as shown in Fig. I or placed on a roll 49 as shown in Fig. IV. One end of the sheet material 12 is placed under a pair of opposed weight like holding members 9 on the belt like member 4 adjacent the plate members 7 and is held by said weight members and carried therewith when the belt 4 is intermittently advanced. Attention is directed to the fact that as the weight like members 9 are intermittently advanced over the roll 3 as shown in Fig. I, the action of gravity causes them to fall away from the belt 4 and automatically release the sheet material 12. Any suitable type of a receptacle such as a hand wagon 74 or the like may be placed adjacent the machine to receive the sheet material when it is released by the weight like holding members 9.

The said weight like holding members 9 are also adapted to automatically drop into engagement with sheet material 12 when they are moved upwardly over the roll 2. This provides automatic means for gripping and holding the sheet material to carry it with the belt like member 4 as the said belt is intermittently advanced and also provides means which will operate automatically to release the sheet material after it has been intermittently advanced over the machine. There is at least one pair of weight like holding members 9 in engagement with the material 12 when the gripping and releasing action of the other of said holding members takes place.

The intermittent advancing of the sheet like material 12 a given amount with the belt like member 4 at each movement thereof facilitates the inspection of the material and provides means by which the material may be measured. The measuring is accomplished by successive movements of a predetermined amount each revolution of the crank member 36.

The cutting operation is performed during the period at which the belt like member 4 is at rest and is accomplished by guiding the rotating cutting disc 35 in the desired path across the material 12. The guide wheel 50 on the cutting device 34 engages with the plate 7 during the cutting operation and prevents the possible forcing of the cutting disc 35 into engagement with the said plate and thereby causing it to become dulled or broken and rendered impractical for use.

Attention is directed to the fact that the plate members 7 are provided with raised longitudinal edges as shown in Figs. I, IV, VI and XII, to provide means by which the cutting disc 35 will en-

gage and cut the sheet material. This is due to the fact that the sheet material bridges over the depressed portion of the plate members and is supported in this position by the raised longitudinal edges of said plates.

The amount of each intermittent movement of the belt like member 4 is controlled by adjusting the link member 24 longitudinally of the slot 51 in the rock lever 20 as shown in Fig. I or by changing the gear member 14 as shown in Fig. IV, 10 wherein a modified form of the invention is illustrated.

In Fig. IV the intermediate gear 15 is mounted in a slide bearing 52 which is slidably mounted in a slotted lever 53. The lever 53 is pivoted at 15 54 adjacent one end thereof to the frame 1 and is connected by a bolt like member 55 to a slotted support plate 56 carried by the main frame 1. The bearing 52 is adapted to be moved longitudinally of the slotted lever 53 to permit the use of 20 different sized gears 14. The said bearing 52 as shown in Fig. X is provided with clamp bolts 57 which are slidably mounted in aligned slots 58 formed in the lever 53 and are adapted to be tightened to secure the bearing 52 in desired ad- 25 justed position on the lever. The lever 53 is then moved on its pivot 54 to place the bearing 52 and gear 15 in desired position intermediate the gears 14 and 16. The bolt 55 is then tightened to rigidly 30 secure the bearing 52 and gear 15 in their ad- justed position.

The roll 49 of sheet material 12 as shown in Fig. IV is mounted on a pair of rolls 126 and 127 positioned adjacent the main drive roll 2. One of the rolls 126 or 127 is rotated by a cone pulley 128 35 or some suitable speed varying means which is driven by a belt 129 and cone pulley 130 or similar means by which the rotating movement of the roll 126 or 127 may be varied. The cone pulley 40 or like means 130 is mounted on the main drive shaft 131 of the machine and is continually rotated during the operation of the machine. The roll 49 of sheet material 12 placed upon the rolls 126 and 127 is adapted to be rotated by said rolls to 45 feed a predetermined amount of the material 12 into a trough or like means 132 mounted on the main frame 1. A predetermined amount of the material 12 is fed into the trough 132 prior to the moving of said material over the machine by the belt like member 4. This is to relieve any pulling strain which might mar and spoil the material 50 during the operation of the main machine.

An auxiliary guide roll or like means 60 positioned adjacent the main roll member 2 provides 55 means for guiding the sheet material 12 over the roll 2 during the operation of the machine.

A modified form of clamp member is shown in Figs. IV, V and VII wherein spring clip members 61 are employed. The said clip members are 60 hingedly attached to the belt like member 4 in a similar manner to that of the weight like members 9. In this instance a cam plate 62 is stationarily secured at each end of the machine adjacent the roll members 2 and 3 and in the path 65 of projecting portions 63 formed on the clip members 61. The plate member 62 adjacent the roll 2, as diagrammatically illustrated in Fig. V, is adapted to cause the clip members 61 to swing upwardly on their pivots away from the belt like member 4 as the said belt like member is intermittently rotated. When the projecting portions 63 of the clip members 61 are moved out of engagement with the cam plate 62 a spring member 64 on each clip causes the said clips to be urged 70 75

towards the belt like member 4 to grip and hold the sheet material 12 on said belt.

A second cam plate, not shown in the drawings, is positioned adjacent the roll member 3 and is adapted to operate in a similar manner to that of the cam plate 62 adjacent the roll 2. When the belt like member 4 is intermittently advanced the said cam plate adjacent the roll 3 is adapted to raise the clip members and cause them to release the sheet material 12 whereupon the said material will fall into the receptacle 74.

In Fig. VIII there is shown a modified form of crank member 36 which comprises a disc 65 having a graduated transverse slot 66 therein in which is slidably mounted a pivot block 67. The block 67 is provided with an indication mark 75 by means of which the position of block in the disc may be determined. The link member 21 in this instance is pivoted at 68 to the pivot block 67 and the said block is moved longitudinally of the slot 66 by a threaded member 69 on which it is threadedly mounted. This provides additional means for varying the intermittent movement of the belt like member 4.

A further modification of the invention is shown in Fig. IX wherein the belt like member 4 is provided with tapered projecting strips 70 which extend longitudinally thereof adjacent each side. The longitudinal strips are adapted to fit within circumferential grooves 71 formed in the face of the rolls 2 and 3. These strips provide means for preventing side movement of the belt like member 4 during the operation of the machine.

A plate member 72 as shown in Fig. I may be attached to the sides of the rolls 2 and 3 to prevent side movement of the belt like member when the tapered rod members 5 are employed. The said plate members 72 are adapted to engage with the ends of the rod members 5 to keep them in proper relation with the rolls 2 and 3 and prevent side movement thereof.

A plurality of auxiliary bearing members 73, as shown in Fig. I, are mounted on the frame 1 to permit the use of different sized belt like members 4. It being simply necessary to place a belt like member of the desired length over the rolls 2 and 3 and employ the bearing 73 necessary for said length of belt like member. In this manner several different lengths of belt like members 4 can be quickly and easily employed. The amount of movement of the belt like member 4 can be quickly adjusted to meet the requirements of the different lengths by changing the gear 14 or by varying the movement of the pawl 19 or crank 36 as shown in Fig. VIII.

In Fig. XI there is shown a modified form of brake member, formed by placing a grooved faced disc 76 on the shaft 18 adjacent the ratchet wheel 17. A hook shaped brake band 77 is mounted in the grooved face of the disc 76 and is formed with a projecting portion 78 which is slidably mounted in a bearing 79 pivoted at 80 to the link member 21.

A spring member 81 is placed on the projecting portion 78 on the end opposite the brake band 77 and the tension thereof is varied by tightening and loosening a nut member 82 which is mounted on the threaded end 83 adjacent the spring. An adjustable collar 84 is mounted on the projecting portion 78 adjacent the bearing 79 to provide means by which the pressure of the brake band 77 may be released as the crank member 36 rotates to advance the ratchet wheel 17. As the crank member moves to its extreme advanced position the bearing member 79 slides on the

projecting portion 78 and causes the spring 81 to compress and force the brake band 77 into frictional engagement with the disc 76. This provides automatic brake means for preventing the accidental advancing of the belt like member 4 more than the desired amount.

A switch member 85 as shown in Fig. I provides means whereby the machine may be started and stopped when desired.

In Figures XII, XIII and XIV there is shown a modified form of cutting device by means of which the sheet material 12 may be automatically cut as it is intermittently advanced over the machine. In this instance the cutting device 34 is mounted on a slide block 86 which is slidably mounted on a slide rod 87 carried by a frame 88 slidably mounted at each end in a pair of vertical bearing members 89 carried by the main frame 1. The cutting device 34 is automatically moved longitudinally of the slide bar 87 by a chain member 90 and cord 91 attached at 92 to the top of the slide block 86. The chain 90 extends over an idler sprocket wheel 93 on the frame 88 and a second sprocket wheel 94 on said frame and is attached at 95 to the cord 91. The cord 91 extends over the idler pulleys 96 and 97 mounted on the opposite side of the frame 88. The chain and cord are moved by a train of gears 98, 99, 100 and 101. The gear 99 is attached to the shaft 102 and the gears 100 and 101 are loosely mounted on said shaft. The gear 100 is rotatably mounted in a bearing 103 carried by the bearing 89 and is held against longitudinal movement on the shaft 102 by said bearing. The gear 101 is rotatably mounted on a reduced slotted extension 104 of a support bearing 105 and is held against longitudinal movement on the shaft 102 by a pin 106 which extends in the slot in said reduced extension. The gears 100 and 101 are provided internally with clutch faces 107 which are adapted to engage with a clutch member 108 mounted on the shaft 102 centrally of said gears. The gears 100 and 101 are in constant engagement with a main drive gear 109 mounted on a horizontal shaft 110 and are adapted to be constantly driven by said gear. The shaft 110 is driven by the pulley 111, belt 112 and pulley 113 mounted on the crank shaft 36 of the main drive mechanism of the machine or it may be driven from any suitable source of power.

A pair of cam discs 114 are mounted on the shaft 110 and are adapted to raise and lower the frame 88 and cutting device 34 during the operation of the machine. The said cams 114 are provided with a cutter advancing dwell surface 115, an intermediate neutral dwell surface 116 and a cutter disengaging and returning dwell surface 117. The dwell surface 115 permits the frame 88 to drop and cause the shaft 102 to slide internally of the gears 100 and 101 and move the clutch member 108 into engagement with the clutch face 107 internally of the gear 101. This causes the shaft 102 to rotate and transmit motion through the gears 98 and 99 to the sprocket wheel 94 which in turn pulls the cord 91 and causes the cutting device 34 to slide longitudinally of the slide rod 87. Attention is directed to the fact that when the frame 88 is in this low position, the sliding cutter member 35 which is driven by the motor 37 will engage with and cut the material 12. The cams 114 are so designed and timed that when the cut is completed the return dwell surface 117 will be moved into play and cause the frame 88 to raise and simultaneously disengage the clutch 75

108 from the gear 101 and force it into engagement with the clutch face 107 of the gear 100. By reason of the fact that the gear 100 is driven in the opposite direction it will cause a reversed motion to be imparted to the chain 90 and cord 91 whereupon the cutting device 34 will be returned to its initial set. When the cutting device 34 is in its initial set position the cams are so timed that the neutral dwell surface comes into place and causes the clutch member 108 to be moved to an intermediate disengaged neutral position between the gears 100 and 101. During the time interval at which the returning and neutral dwelling movement of the cams 114 is taking place the machine operates to advance the material 12 for the next cut. This action is constantly repeated during the operation of the machine and thereby provides automatic means for conveying, measuring and cutting the sheet material to desired lengths.

It is apparent that during the operation of the machine the operator can inspect the sheet material as it is intermittently moved over the belt like member and make any adjustments which might be necessary.

The slide rod 87 is formed with grooved side walls 118 in which are mounted a pair of electrical conducting rod members 119. The rod members 119 are insulated from the slide rod 87 by grooved support plates 120 of any suitable insulation material. The rods are adapted to conduct electrical energy to the motor 37 through the spring contacts 121 which slidably engage with the electrical conducting rods 119 when the cutting device 34 is moved longitudinally of the slide rod 87. The electrical conducting rod members 119 are connected by the lead wire 122 to a knife switch 123, one portion of which is mounted on the frame 38 and the other portion on the adjacent support bearing 89. The knife switch is connected by the lead wires 124 to any suitable source of power.

It is apparent that when the frame 38 is in its lowest position the knife switch 123 will be closed and that electrical energy will be transmitted to the motor 37 to rotate the cutting disc 35 and that when the frame 38 and cutting device 34 are in their raised and inoperative positions the knife switch will be opened or disengaged and no electrical energy will be transmitted to the motor.

The amount of movement of the cutting device 34 longitudinally of the slide bar 87 can be controlled by the length of cutting dwell on the cam members 114 and in this manner the length of the cut may be varied as desired, it being simply necessary to form a relatively short cutting dwell on the cam or a long cutting dwell. It is apparent that when different lengths of cuts are necessary during a continued operation of the machine the cams 114 can be provided with a plurality of cutting dwells of the desired lengths.

An automatic recording device 125 is geared with the roll 2 and is rotated thereby during the intermittent operation of the machine. The purpose of this recording device is to provide means by which the total amount of material 12 which passes over the machine can be determined.

The general operation of the machine is as follows:

The end of the sheet material 12 is first placed under an opposed pair of holding members 9 or 61 adjacent the roll 2 and the machine is started. As the belt like member 4 is intermittently advanced the sheet material 12 is carried therewith

over the machine. During the time interval at which the machine is idle, that is, between each intermittent movement, the cutting device 34 is operated to cut the material. Each intermittent movement of the belt like member 4 advances the sheet material 12 a given amount over the machine and thereby provides means for measuring the material. The amount of movement is controlled by the mechanical adjustments of the machine and the length of the belt like member 4 employed, as has been previously described.

Attention is directed to the fact that the amount of movement of the belt like member is such that the plate members 7 are intermittently moved to a definite predetermined position on the machine and that this position is where the cut is to be made, either with the manually operated cutting device, automatic cutting device or with a separate cutting device such as shears or the like as desired.

The total amount of material which has passed over the machine each day is recorded on an automatically operating recording device 125 intermeshed with the roll 2, it being simply necessary to take the readings at the start and close of the day and calculate the total amount from these readings.

The intermittent movement of the machine permits thorough inspection and provides ample time for minor adjustments that might be necessary.

The machine is simple in its construction and operation, requires but little floor space and may be used for any one of the above purposes or in any combination one with the other.

From the foregoing description it will be seen that I have provided simple, efficient and economical means and processes of obtaining all of the objects and advantages of the invention.

Having described my invention I claim:

1. In a device for advancing a sheet to an operating point for the performance of a manually controlled operation thereon, a table member having a movable top portion thereon, a plurality of position locating members on said top portion for registration with the operating point and lying in a plane substantially parallel with said top portion, means associated with the table member for intermittently moving said top portion and position locating members an amount substantially equal to the distance between said position locating members and to move said position locating members successively to said operating point adjacent the table and intermediate its ends to permit the performance of the manually controlled operation, said position locating members forming means over which the sheet placed on the table top is adapted to extend to locate the operating point on said sheet and means associated with the top portion for causing the sheet to move with said top portion to assume its desired relation with the position locating members without altering the relation of said means and position locating members during said intermittent movement.

2. In a device for advancing a sheet to an operating point, a table member having a movable top portion thereon, a plurality of material elevating members on said top portion and having intermediate relatively flat portions for registration with the operating point and lying in a plane substantially parallel with said top portion, means associated with the table member for intermittently moving said top portion and material elevating members an amount substantially equal to the distance between said elevating members

and to move said elevating members successively to said operating point adjacent the table and intermediate its ends, said elevating members forming means over which the sheet placed on the table top is adapted to be bridged and elevated to locate the operating point on said sheet and means associated with the top portion for causing the sheet to move therewith to assume its bridged and elevated relation with the elevating members without altering the relation of said means and elevating members during said intermittent movement.

3. In a device for advancing a sheet to an operating point, a table member having a movable top portion thereon, a plurality of spaced plate like members having raised longitudinal edges and an intermediate relatively flat portion lying in a plane substantially parallel with said top portion, means associated with the table member for intermittently moving said top portion and plate like members an amount substantially equal to the distance between said plate like members and to move said plate like members successively to said operating point adjacent the table and intermediate its ends, said raised longitudinal edges of the plate members forming means over which the sheet placed on the table top is adapted to be bridged and elevated to locate the operating point on said sheet and means associated with the top portion for causing the sheet to move therewith to assume its desired relation with the plate members without altering the relation of said means and plate members during said intermittent movement.

35. 4. In a device for advancing a sheet to an operating point, a table member having a movable top portion thereon, a plurality of position locating members for registration with the operating point and lying in a plane substantially parallel with said top portion, means associated with the table member for intermittently moving said top portion and position locating members an amount substantially equal to the distance between said position locating members and to move said position locating members successively to an operating point adjacent the table and intermediate its ends and means for changing the amount of movement of the intermittently moving means

and for altering the related positions of the plurality of spaced position locating members in corresponding amounts, said position locating members forming means over which the sheet placed on the table top is adapted to extend to locate the operating point on said sheet.

5. In a device for advancing a sheet to an operating point, a main support, a movable carrying member on said main support having holding means for gripping and moving the sheet with said carrying member and having a plurality of position locating members thereon for registration with the operating point and lying in a plane substantially parallel with its longitudinal surface and means incorporating gears and a ratchet associated with said carrying member for intermittently moving it together with the holding means and the plurality of position locating members successively longitudinally of the main support to move said position locating members substantially to said operating point adjacent the carrying member and intermediate its ends, said position locating members forming means over which the sheet moved with the carrying member is adapted to extend to locate the operating point on said sheet.

6. In a device for advancing a sheet to an operating point, a table member having a movable top portion thereon, a plurality of position locating members for registration with the operating point and lying in a plane substantially parallel with said top portion, means associated with the table member for intermittently moving said top portion and position locating members an amount substantially equal to the distance between said position locating members and to move said position locating members successively to an operating point adjacent the table and intermediate its ends and means for changing the extent of movement of the intermittently moving means by an amount sufficient to advance a set of said position locating members successively to said operating point, said position locating members forming means over which the sheet placed on the table top is adapted to extend to locate the operating point on said sheet.
